UNITED STATES PATENT OFFICE.

WILLIAM S. HADAWAY, JR., OF NEW ROCHELLE, NEW YORK, ASSIGNOR TO THE CUTLER-HAMMER MFG. CO., OF MILWAUKEE, WISCONSIN, A CORPORATION OF WISCONSIN.

HEATER FOR TYPE-SETTING MACHINES.

1,284,189.

Specification of Letters Patent.

Patented Nov. 5, 1918.

Application filed March 26, 1914. Serial No. 827,361.

To all whom it may concern:

Be it known that I, WILLIAM S. HADAWAY, Jr., a citizen of the United States of America, and a resident of New Rochelle, 5 Westchester county, and State of New York, have invented certain new and useful Improvements in Heaters for Type-Setting Machines, of which the following is a specification, reference being had to the accompanying drawings, forming a part thereof.

My invention relates to heaters and particularly to electric heaters for the melting pots of type-setting machines.

One object of my invention is to provide 15 an economical electric heater for linotype crucibles and other melting pots of this character.

Another object is to provide means for 20 supplying heat to the mouth and throat of melting pots of the aforesaid character in addition to maintaining the metal in the body of the pot in a suitable condition.

Another object is to provide a plurality of 25 removable armored electric heaters particularly adapted to be applied to the mouth and throat of a type-setting machine pot, and means for increasing their efficiency and effectiveness by holding them in position under pressure.

Another object is to provide a heating 30 appliance for the mouth and throat arranged to impart a relatively large quantity of heat near the mouth of the crucible.

In addition to the foregoing, my invention 35 is applicable directly and without material adaptation to pots of standard construction so that the pots of old machines may be easily equipped with my invention.

Other objects and advantages of my invention will be set forth hereinafter, and in order that my invention may be thoroughly understood, I will now proceed to describe 40 the same in the following specification and then point out the novel features thereof in appended claims.

In the drawings:

Figure 1 is a sectional elevation taken on the line 1—1 of Fig. 2 of a type-setting machine pot equipped with and embodying my 45 invention.

A partially sectional plan view of the same device is shown in Fig. 2.

Figs. 3, 4, 5 and 6 are detail views of the mouth and throat heaters and clamps.

Like characters of reference designate corresponding parts in all the figures.

10 is a crucible which is formed in a well known manner and has a throat 11, a mouth 12 and a plunger well or socket 13. The crucible is set into a loose jacket 15, the 15 spaces 16 around and beneath the crucible being filled with some suitable heat insulating material such as nonpareil.

The jacket and crucible are closed by a cover hinge-connected by a pin 21 which is 20 supported on lugs 22 of the jacket. A small opening is provided in the cover which is adapted to be closed by a hinge-connected lid or auxiliary cover 23. The covers 20 and 23 have insulating blocks 24 secured to them 25 by screws or bolts 25 as clearly indicated in Fig. 1 in order to prevent the loss of heat in an upward direction, the side walls and bottom of the crucible being protected by the insulation in the spaces 16. A ring or loop 30 30 is welded or otherwise secured to the crucible at one side and loosely encircles the bottom of the crucible. Opposite this point of attachment it is provided with a lug or thickened portion 32 through which a clamp- 35 screw 33 extends.

The jacket 15 has a removable bottom plate 17 to which is secured, and from which depends, a rectangular casing 18. The jacket is provided with legs or supports 19, one of 40 which is indicated in Fig. 1.

The under surface of the throat 11 is cylindrically curved and an electric heater 40 which is correspondingly curved, is adapted to be held in contact with it by a clamp or 45 shoe 42. The clamp is shown in detail in Fig. 3 and is provided with lugs or ears 43 near its upper end and a single lug 44 near its lower end. Its outer surface is provided with ribs 45 in order to increase its rigidity.

The ring 30 is flattened on one side to permit not only the throat heater 40 but also the throat clamp 42 to extend through it, the arrangement of parts being such that when the heater and clamp are in position the lug 44 is directly opposite the screw 33 which acts upon it. By tightening the screw the lower part of the clamp 42 is forced inwardly and holds the adjacent portion of the

heater in close engagement with the cylindrically curved surface of the throat 11. The clamp is provided near the upper end with a transverse rod 50 which extends 5 through the lugs or ears 43 and beyond the sides of the throat, a pair of eyebolts 51 being secured to its ends and located on the respective sides of the throat. They extend upwardly, as shown in Fig. 1, through holes 10 53 which are provided for this purpose in another clamping member 54 located over the mouth of the crucible. This clamp is curved to correspond to the upper cylindrically curved surface 55 of the mouth which 15 is provided with a heater 56. This clamp, which may be referred to as a clamp for the mouth heater, obviously co-operates with the upper end of the clamp for the throat heater in holding the mouth heater and the upper 20 end of the throat heater in close contact with their engaging surfaces when the nuts 57 are tightened. As clearly shown in Fig. 2 the nuts 57 are accessible when the cover 20 is open. In order that access may be had to 25 the screw or bolt 33, a hole 60 is provided in the side of the jacket 15 through which a socket wrench or other suitable implement may be thrust.

In order that the insulating material, 30 which fills the spaces 16, may not interfere with the ready removal of the heater 40, a partition or inner casing 65 is provided adjacent to the throat of the crucible. It is suitably spaced from the crucible to leave 35 room for the clamp 42 and the heater 40. Furthermore, a bushing 66 of fiber or other suitable material is fitted into the hole 60 and extends inwardly to the inner casing 65.

The heaters 40 and 56 may be constructed 40 in any suitable manner, and I prefer to employ a heater of the so-called "armored" type which is sealed in sheet metal and hence is not injured if molten metal is thrown into contact with it when the type-setting machine is in service.

The heater illustrated in Figs. 4 and 5 comprises armor plates 70 and 71 which are welded together at their edges and suitable insulated resistor strips or ribbons 72. As 50 clearly shown in Fig. 4 the upper part of the heater is wider than the lower end, thus more heat is generated close to the mouth of the crucible where heat is obviously most needed. The heat generated in both heaters is quickly transferred to the walls of the crucible and keeps them at a sufficient temperature so that when the molten metal is forced through the relatively narrow opening of the throat it is maintained in suitable condition for casting.

The heater 40 is provided with the narrow lead arm 40^a which extends materially below the bottom of the jacket, in order that the terminals may be protected from short-

circuit or injury, any molten metal which accidentally flows down the surfaces of the heater being chilled and solidified on the lead arm before it reaches the exposed terminals.

The terminals themselves are specially designed to permit the removal of the heater, each of them comprising a hollow metal rivet which is substantially flush with the surfaces of the heater.

The lead arm 40^a is protected by the rectangular box or casing 18 which incloses a cooling chamber that is suitably insulated from the hot melting pot.

The metal in the pot of the crucible may be melted and held at a proper temperature 80 by any suitable means such as, for example, a pair of cylindrically curved heaters 75 and 76, the terminals 77 of which extend laterally outward at the top into a terminal box 78. The two heaters 75 and 76 are preferably designed so that either of them is sufficient alone to melt the metal in the pot and thereby permit the removal of the other for replacement or repairs, it being unlikely that both will be inoperative at the same 90 time.

It is evident from the foregoing that it is only necessary to loosen the nuts 57 and the screw 33 in order to freely remove the mouth and throat heaters. They may 95 therefore be readily replaced in case they are injured or destroyed.

The immersion heaters which melt the metal in the crucible, are of course necessarily armored in order that the insulation for the resistance conductor may be protected from injury. I have found however, that the throat and mouth heaters are subjected to substantially the same hazard by reason of the fact that in operation a 100 considerable amount of molten metal is 105 likely to be thrown onto the mouth and throat heaters and adjacent parts by reason of the pressure under which the casting process is accomplished.

The combination of heaters which I employ is particularly efficient in operation because a large proportion of the heat is generated in the immersion heaters where the demand is greatest and where the loss of 110 heat is least. The body of the melting pot receives new slugs of solid metal to be melted and is most fully protected by the heat insulation. Furthermore, the metal which surrounds the immersed heaters is 115 frequently agitated by the action of the plunger in the well 13 and therefore the heaters are not coated with oxidized metal 120 which would interfere with the transfer of heat to the metal.

Attention is particularly directed to the fact that the mouth and throat heaters are arranged to impart a relatively large quan-

tity of heat near the mouth of the crucible and by this means a considerable economy is effected by avoiding the application of unnecessary heat to other places and by the 5 concentration of heat near the mouth of the discharge opening which is at a considerable distance from the body of the crucible and where it is most important to insure a proper temperature of the metal since the 10 molten metal goes directly from the mouth of the crucible to the mold.

My invention is not restricted to the specific arrangement shown and described and I intend that only such limitations be imposed as are indicated in appended claims. 15

What I claim is:

1. A heater for type-setting machine melting pots comprising a curved throat heater, a mouth heater, and a single means for 20 pressing both heaters into contact with their engaging surfaces.

2. A heater for type-setting machine melting pots comprising a curved throat heater, a mouth heater, a clamping plate over the 25 mouth heater, a second clamping plate over the throat heater, and a single clamp for forcing the clamping plates against their respective heaters.

3. A heater for type-setting machine melting pots comprising a curved throat heater, a mouth heater, a clamping plate over the mouth heater, a second clamping plate over the throat heater, a single clamp for forcing the clamping plates against their respective 35 heaters, and independent means for forcing one end of the throat clamp into contact with the adjacent end of the throat heater.

4. In combination with a type-setting machine crucible having a body and a curved 40 throat extension, of a heater unit curved to cooperate with the surface of the throat and wider near the outer end of the throat extension, a correspondingly curved clamp, and means for forcing the clamp inwardly 45 to press the heater against the surface of the crucible.

5. In combination with a type-setting machine crucible having a body and a curved throat extension, of a pair of heater units 50 adapted to conform to opposite surfaces of the throat clamping plates arranged to engage heaters, and means for forcing clamping plates toward each other to press the heaters against their engaging surfaces.

55 6. In combination with a type-setting machine crucible having a body and a curved throat extension, of a mouth heater above the throat adjacent to the opening, a relatively long throat heater coöperating with 60 the under surface of the throat, a clamping plate fitted over the mouth heater and having perforated lugs, a clamping plate fitted over the throat heater, a transverse rod secured to the clamp, and tie bolts mounted

on the respective ends of the rod and extending on opposite sides of the throat extension through the perforated lugs of the mouth heater clamp. 65

7. In combination with a type-setting machine crucible having a body and a curved throat extension, of a mouth heater above the throat adjacent to the opening, a relatively long throat heater coöperating with the under surface of the throat, a clamping plate fitted over the mouth heater and having perforated lugs, a clamping plate fitted over the throat heater, a transverse rod secured to the clamp, tie bolts mounted on the respective ends of the rod and extending on opposite sides of the throat extension 70 through the perforated lugs on the mouth heater clamp, and means for forcing the lower end of the throat clamp inwardly to press the lower part of the throat heater into contact with the adjacent surface of the 75 crucible.

8. In combination with a type-setting machine crucible having a body and a curved throat extension, of a mouth heater above the throat adjacent to the opening, a relatively long throat heater coöperating with the under surface of the throat, a clamping plate fitted over the mouth heater and having perforated lugs, a clamping plate fitted over the throat heater, a transverse rod secured to the clamp, a loop secured to the crucible at one side and loosely surrounding its lower end, and a clamping screw extending inwardly through the loose end of the loop into engagement with the throat clamp 90 to force it inwardly and press the heater against adjacent surface of the crucible. 95

9. A heater for type-setting machine melting pots comprising a curved armored throat heater, an armored mouth heater, and means 100 for pressing both heaters into contact with their engaging surfaces.

10. A heater for type-setting machine melting pots comprising a curved armored throat heater, an armored mouth heater, a 110 clamping plate over the mouth heater, a second clamping plate over the throat heater, and a single clamp for forcing the clamping plates against their respective heaters. 115

11. A heater for type-setting machine melting pots comprising a curved armored throat heater, an armored mouth heater, a clamping plate over the mouth heater, a second clamping plate over the throat 120 heater, a single clamp for forcing the clamping plates against their respective heaters, and independent means for forcing one end of the throat clamp into contact with the adjacent end of the armored throat heater. 125

12. A heater for type-setting machine melting pots comprising a plurality of curved heaters of different sizes around the

plunger well and adapted to be immersed in the molten metal.

13. A heater for type-setting machine melting pots comprising a curved throat heater having a sealed metal armor, a lead arm extending beyond the melting pot, and substantially flush terminals secured to said arm.

14. In combination with a type-setting machine crucible having a body, a plunger well therein, and a curved throat extension, of a removable throat heater comprising a body adapted to engage the curved throat extension, and a lead arm extending downwardly beyond the bottom of the crucible.

15. In combination with a type-setting machine crucible having a body, a plunger well therein, and a curved throat extension, of a removable throat heater comprising a body adapted to engage the curved throat extension and a lead arm extending downwardly beyond the bottom of the crucible, a jacket or outer casing for the crucible, and heat insulation within the jacket around the crucible.

16. In combination with a type-setting machine crucible having a body, a plunger well therein, and a curved throat extension, of a removable throat heater comprising a body adapted to engage the curved throat extension and a lead arm extending downwardly beyond the bottom of the crucible, a jacket or outer casing for the crucible, a removable clamp within jacket and adapted to press the body of the heater into contact with the adjacent surface of the crucible, and heat insulation within the jacket around the crucible and its heater.

17. A heater for type-setting machine crucibles comprising a throat heater, a loop secured to the crucible at one side and loosely surrounding its lower end, a clamping shoe for the heater extending through the opening in the loop, and a clamping bolt screwed inwardly through the loose end of the loop into engagement with the clamping shoe to force the shoe inwardly and press the heater against the adjacent surface of the crucible.

18. A heater for type setting machine melting pots comprising a heater in the molten metal in the body of the pot, and means for imparting heat to the outlet of the pot.

19. In combination with a type setting machine crucible having a body, a plunger well therein, and a throat extension, of an electric heater in the pot around the plunger well in contact with the molten metal therein, and means for imparting heat to the mouth and throat.

20. In combination with a type setting machine crucible having a body, a plunger well therein and a throat extension, of an armored electric heater in the pot around

the plunger well in contact with the molten metal therein, and an external electric heater for imparting heat to the mouth and throat.

21. In combination with a type setting machine crucible having a body, a plunger well therein and a throat extension, of an armored electric heater in the molten metal in the pot around the plunger well, and an external electric heater adapted to impart heat to the mouth and throat and arranged to impart a greater quantity of heat near the outlet of the crucible.

22. In combination with a type setting machine crucible having a body, a plunger well therein and a throat extension, of an electric heater in the molten metal in the pot around the plunger well, an external heater for the throat, and an electric heater for applying additional heat near the mouth.

23. A heating appliance for a type setting machine crucible comprising an electric throat heating means arranged to apply a greater quantity of heat near the outlet of the crucible.

24. A heating appliance for a type setting machine crucible comprising an electric heater adapted to impart heat to the throat of the crucible and having a greater heat generating capacity near the mouth of the crucible.

25. A heating appliance for a type setting machine crucible comprising an electric heater adapted to impart heat to the throat of the crucible, and means for imparting additional heat near the mouth of the crucible.

26. A heating appliance for a type setting machine crucible comprising an electric heater adapted to impart heat to the throat of the crucible, and an additional heater for imparting heat near the mouth of the crucible.

27. In combination with a type setting machine crucible having a body, a plunger well therein, and a throat extension, of an electric heater in the molten metal in the pot around the plunger well.

28. A heater for typesetting machine melting pots comprising a throat heater, a mouth heater, and means for pressing both heaters into contact with their engaging surfaces.

29. A heater for typesetting machine melting pots comprising a heater for the metal in the body of the pot, a heater adapted to impart heat to the throat of the crucible, and a mouth heater.

30. A heater for a typesetting machine melting pot comprising a heater for the metal in the body of the pot and disposed therein, and means for imparting heat to the throat and mouth of the pot.

31. The combination with a typesetting machine crucible adapted to contain type metal, and heating means therein and ex-

tending sufficiently near the top of the metal to prevent melting of the type metal at the bottom before it is melted at the top.

32. The combination of a typesetting machine crucible adapted to contain type metal, and heating means within the crucible arranged in the type metal and adapted to impart its heat thereto.

In witness whereof I have hereunto set my hand in the presence of two subscribing ¹⁰ witnesses, this 24 day of March, 1914.
